UNITED STATES PATENT OFFICE.

SIEGMUND BACHMANN, OF CHICAGO, ILLINOIS.

BOX.

1,297,636.

Specification of Letters Patent. Patented Mar. 18, 1919.

Application filed November 29, 1918. Serial No. 264,659.

To all whom it may concern:

Be it known that I, SIEGMUND BACHMANN, a citizen of the United States, residing at Chicago, in the county of Cook and State 5 of Illinois, have invented a new and useful Improvement in Boxes, of which the following is a specification.

My invention relates to improvements in boxes more commonly formed of flexible 10 box-board and involving a base, surrounding walls extending upwardly from the base, corner extensions connected with the walls of the box, and means engaging the said extensions when the box is in erected 15 condition, for holding the box against collapsing.

My primary object is to reduce the cost of construction of boxes of the type referred to, without impairing their resistance to 20 collapsing, when in erected condition, my invention involving to this end, the use of the minimum amount of box-board.

Referring to the accompanying drawings:—

25 Figure 1 is a perspective view, with certain parts broken away, of a box of the hat-box type constructed in accordance with my invention. Fig. 2 is a plan view showing a corner portion of the box blank from 30 which the box of Fig. 1 is constructed. Fig. 3 is a broken section, taken at the line 3 on Fig. 1, and viewed in the direction of the arrow. Figs. 4 and 5 are sections taken at the lines 4—4, and 5—5, on Fig. 3 and 35 viewed in the direction of the respective arrows. Fig. 6 is a plan view of a corner portion of a blank for forming a box constituting another embodiment of my invention. Fig. 7 is a broken sectional view of the 40 box formed from the blank of Fig. 6, this section corresponding with Fig. 3; and Fig. 8, a section taken at the line 8—8 on Fig. 7 and viewed in the direction of the arrow. Fig. 9 is a plan view of a corner portion of 45 another blank for forming a box constituting another embodiment of my invention. Fig. 10 is a broken section of the box formed from the blank of Fig. 9, this section corresponding with Fig. 3; and Fig. 11, a section 50 taken at the line 11—11 on Fig. 10, and viewed in the direction of the arrow. Fig. 12 is a plan view of a corner portion of another blank for forming a box constituting another embodiment of my invention. 55 Fig. 13 is a broken section of the box formed from the blank of Fig. 12, this section cor-

responding with Fig. 3; and Fig. 14, a section taken at the line 14—14 on Fig. 13 and viewed in the direction of the arrows. Fig. 15 is a plan view of a corner portion of another blank for forming a box constituting another embodiment of my invention. Fig. 16 is a broken section of the box formed from the blank of Fig. 15, this section corresponding with Fig. 3; and Fig. 17, a section taken at the line 17—17 on Fig. 16 and viewed in the direction of the arrows. Fig. 18 is a plan view of a corner portion of another blank for forming a box constituting another embodiment of my invention. Fig. 19 is a view like Fig. 18 showing one of the walls and the corner extensions illustrated in this figure folded over the adjacent portion of the blank; and Fig. 20, a view like Fig. 3 of this portion of the box 75 when erected. Fig. 21 is a plan view of a corner portion of another blank for forming a box constituting another embodiment of my invention. Fig. 22 is a view like Fig. 21 with a wall and the corner extension 80 shown folded over upon adjacent portions of the blank and with the locking flap turned upwardly. Fig. 23 is a section like Fig. 3, of this portion of the box, showing it in erected condition. Fig. 24 is a plan 85 view of a corner portion of another blank for forming a box constituting another embodiment of my invention. Fig. 25 is a view like Fig. 19, with a wall and the corner extension shown folded over upon adjacent 90 portions of the blank. Fig. 26 is a section like Fig. 3, of this portion of the box, showing it in erected condition; and Fig. 27 is a section taken at the line 27 on Fig. 26 and viewed in the direction of the arrow. 95

Referring to Figs. 1, 2, 3, 4, and 5, one of the four similar corner portions of the blank from which the box of these figures is constructed, is illustrated in Fig. 2, the blank consisting of a rectangular sheet of box-board adapted to be folded along the parallel lines 24 and 25, these lines being shown in Fig. 1, which define a base-portion 26 with box walls 27 and 28 hingedly connected therewith along the lines 24 and 25, 100 the lines 24 and 25 being, by preference, creases to facilitate folding the parts. The lines 24 and 25 intersect each other to form the four corner portions or corner extensions 28', one only of which is shown in Fig. 2, which are hingedly connected with 105 the ends of the walls 27 and 28 along the

outer extremities of the lines 24 and 25 as shown, each of the corner extensions being provided with a diagonal folding line 29 which extends from the point of intersection 5 of the folding lines 24 with the folding lines 25 toward the outer extremities of the corner extensions. In the particular construction shown, the edge portion 30 of each corner extension 28' is cut-away as indicated 10 at 31, the outer ends of the diagonal lines 29 coinciding with these cut-away portions. Also, the outer edges of the walls 27 and 28 are provided with flaps 32 and 33 respectively connected therewith along folding lines 34 and 35.

The diagonal folding lines 29 divide the extensions 28' into two sections 36 and 37 which are hingedly connected together along the folding line 29 and are respectively hinged to the walls 27 and 28 along the folding lines 24 and 25. The section 37 of each corner extension is provided at an edge thereof with a flap 38 connected thereto along a folding line 39 which is substantially in line with the folding line 35, the flaps 38 and 33 being separated by the space 40 and the corner section 37 being severed along lines 41 and 42 to form a lap 43 for a purpose hereinafter described.

The box may be formed from the blank as stated, as follows: By turning the opposite walls 27 upwardly and inwardly, and with them the corner extensions, to cause the walls 27 to overlie the base 26 and the corner 35 extensions to overlie the walls 28. The inner ends of the laps 43 may then be secured to the walls 28 in any suitable manner as by means of the staples indicated at 44, which leaves the outer extremities of the laps 43 free to be flexed, the inner portions of the sections 37 being secured in fixed relation to the walls 28 in any suitable manner, as for example by stapling means, these means in the illustrated construction being a single staple represented at 45 which passes through the sections 37 of both corner extensions at one end of the box, due to the fact that in the particular constructions shown, the proportions of the box are such that the sections 37 overlap each other. To erect the box, the operator swings the walls 27 upwardly and outwardly and the walls 28 upwardly and inwardly along their hinged connections with the base 26 to a 55 position in which these walls extend at right-angles to the base 26. In thus manipulating the structure, the sections 36 swing at their hinged connections with the sections 37 and walls 27 along the folding lines 29 and 24, respectively, to a position where they lie flatwise against the adjacent sections 37 of the corner extensions, as illustrated in the drawing, the operator in this operation springing the outer ends of the laps 43 in an upward direction to permit

of the upper edges of the sections 36 swinging back of these laps, whereupon, on releasing the grasp on these laps, they will spring into overlapping position relative to the sections 36 for holding the latter in place and therefore the walls of the box in erected condition. The flaps 38 in this operation are folded to lie between the sections 37 and the walls 28 as shown in Fig. 5, thus forming a reinforcement for the upper edge of the box; and the flaps 32 and 33 are bent to extend inwardly, preferably at a right-angle to the walls of the box, to form a reinforcing flange extending continuously around the top of the box, certain 80 of these flaps in Fig. 1 being shown broken away to disclose details which would otherwise be hidden.

The construction illustrated in Figs. 6, 7, and 8, is the same as that shown in the preceding figures, except that the flaps 32, 33, and 38 are omitted and instead of cutting the lap 43, as shown in Fig. 2, this lap, represented in Figs. 6, 7, and 8, at 46, is cut from the corner section 37 along the line 47 curved at its ends as indicated at 48. The blank may be folded as described of that of the preceding figures, but instead of providing a single staple 44 for each lap 46, each lap 46 is preferably stapled along its upper edge to the underlying wall 28 by the plurality of staples represented at 49. The lower edges of the laps 46 are therefore adapted to be swung out of the path of movement of the corner sections 36 in the 100 erecting of the box and when released, after erection, overlap the sections 36 and hold the box in erected condition. In the construction illustrated in Figs. 9, 10, and 11, the walls 28 and corner-sections 37 are provided with flaps represented at 50 and 51 connected with these walls and sections along folding lines 52 and 53, the sections 37 being provided with locking flaps 54 corresponding with the locking flaps 43 of Fig. 2 which are cut from the section 37 along the lines 55, 56, and 57, the line of severance running from one point on the folding line 53 to another point thereon, as shown. The blank is folded as described of the blank 115 of Fig. 2, the flaps 51 overlying the flaps 50, and the fastening device, as for example, a staple 54^a securing each lap 54, at its inner end, to the box against the walls 28. The outer ends of the laps 54 are thus left 120 free to be flexed for overlappingly engaging the sections 36 of the corner extensions for holding the box walls in erected condition. The flaps 50 and 51 may be turned inwardly to reinforce the upper edges of the box as explained of the flaps 32 and 33 in Fig. 1.

The construction illustrated in Figs. 12, 13, and 14, is substantially the same as that illustrated in Figs. 1 to 5, inclusive, except that the flaps 32 and 38 are omitted. In 130

this construction wherein the parts are given the same designation throughout as in Figs. 1 to 5, inclusive, the flaps 33 at opposed portions of the box, after the corner extensions 28 and the walls 27 have been folded over upon the base 26 and walls 28 as described in connection with these preceding figures, are folded upwardly and inwardly and then downwardly to overlie the laps 43 as represented, the staples 44 passing also through the flaps 33, and while the laps 43 are entirely severed at their outer ends, from the corner sections 37, the overlapping portions of the flaps 33 operate to hold these laps against displacement.

It will be noted that all of the constructions described are of the so-called automatic box type or, in other words, are of that type of box which may be erected from collapsed condition without requiring the application of fastener devices to the box after erecting it, or the tucking of tongues or the like into slits to effect the locking function. However, my invention is also applicable to boxes of what might be termed the non-automatic type, the embodiment of my invention in three different forms of boxes of this last-referred-to type being illustrated in Figs. 15 to 23, inclusive.

Referring particularly to the construction illustrated in Figs. 15, 16, and 17, one of the similar corner portions of the blank from which this form of box is made is illustrated in Fig. 15, this blank having parallel folding lines 57 and 58, corresponding with the folding lines 24 and 25 of Fig. 1 and forming a rectangular base portion 59 with surrounding wall-portions 60 and 61 corresponding with the wall-portions 27 and 28 of Fig. 1. The lines 57 and 58 at the four corners of the box blank intersect and beyond their points of intersection form the corner extensions 62, each of which has a diagonal folding line 63, and a flap portion 64 hinged at 65 and extending in line with a flap portion 66 hinged at 67 to the outer edge of the adjacent wall-portion 61 at opposite edges of the blank, the flaps 64 and 66 being preferably connected together along a folding line 68, as shown of one part in Fig. 15. The diagonal folding line 63 of each corner extension 62 divides the latter into two triangular corner sections 69 and 70, the sections 70 having cut therefrom along the lines 71, 72, and 73, a tongue 74 which extends up to the folding line 65, and the corner section 69 contains a slit represented at 75 and extending preferably at a right-angle to the folding line 65 when the blank is in the flat condition shown in Fig. 15. In forming a box from the blank of Fig. 15, the side walls 60 and corner extensions 62 may be folded upwardly and downwardly to oppose the base 59 and walls 61 in which condition the flaps 64 are secured to

the underlying flaps 66 by any suitable means as, for example, staples, as indicated at 76. To erect the box, the walls 61 are swung upwardly and toward each other on the base 59 and the walls 60 are swung upwardly and away from each other on the base, the corner sections 69 swinging along the diagonal lines 63 and the lines 57 to a position in which they extend at right-angles to the walls 60 and flat-wise oppose the adjacent corner sections 70, the operator in this movement of the parts lifting the tongues 74 to clear those edges of the corner sections 69 which extend uppermost when the box is erected, as indicated at 77. The tongues 74, one for each corner of the box, thus extend inwardly beyond the corner sections 69 and may be inserted through the slits 75 to extend at their lower portions between the sections 69 and 70, and overlap both of these sections at their upper portions, thus securely holding the box in erected condition. The flap portions 64 and 66 may be turned inwardly to the angular position shown particularly in Fig. 17, wherein they form a reinforcement for the upper edge of the box.

The construction shown in Figs. 18, 19, and 20, is the same as that illustrated in Figs. 15, 16, and 17, except that the flaps 64 and 66 are omitted and the locking tongues, represented at 78 and corresponding with the locking tongues 74 of the preceding figures, extend short of the edges of the corner sections 70, considering the position shown in Fig. 18, and the edges of the corner sections 69 which are uppermost when the box is erected are cut away as indicated of the one section at 79 in the drawing. In this construction of box, the corner sections 70 are secured to the underlying walls 61 as by means of staples 80 preferably at the points indicated in Fig. 19. In the erecting of this construction, the parts are manipulated and interlocked as explained of the construction shown in Figs. 15, 16, and 17.

The construction illustrated in Figs. 21, 22, and 23, is like that of Fig. 15, except that the tongue represented at 81 is of the hook variety, the tongue-receiving slot represented at 82 and corresponding with the slot 75 of Fig. 15, extends at a different angle, the outer edges of the sections 69 are cut away, as indicated at 83, and the adjacent edges of the flaps 64 and 66 are separated, as indicated at 84. In forming the blank into a box, the walls 60 and corner extensions 62 are manipulated as described of the construction in Fig. 15, and fastening means are passed through the sections 70 and walls 61, as indicated at 85, the fastening devices shown being staples, the flaps 64 in this operation being turned along the folding lines 65 to extend between the corner sections 70 and the walls 61, it being preferred that the

flaps 64 be glued to the walls 61 in the position stated, and that the flaps 66 be turned over to overlie the upper edges of the tongues 81 to which latter the flaps 66 are preferably glued. In erecting the box, the walls 60 and 61 are swung on the base 59 as described of the construction illustrated in Fig. 15, the operator in this operation swinging the tongues 81 and with them the flaps 66 upwardly to extend out of the path of movement of the corner sections 69 in swinging to a position in which they lie against the corner-sections 70 (Figs. 22 and 23), the tongues 81 and flaps 66 being then swung downwardly, the tongues 81 to overlie the corner sections 69, these tongues being then inserted at their hook ends into the slots 82 to hold the box in erected condition.

Referring to the construction shown in Figs. 24, 25, 26, and 27, which shows another construction of so-called automatic type and embodying my invention, this construction is substantially the same as that disclosed in Figs. 1 to 5, inclusive, except that the flaps 38 and 33 are preferably connected together along a folding line 86, the same numerals being applied to those parts of the box structure shown in Figs. 24, 25, 26, and 27, as designate corresponding parts in Figs. 1 to 5, inclusive. The blank of Figs. 24, 25, 26, and 27, is folded as explained of the construction in Figs. 1 to 5, inclusive, except that the laps 33 and 38 are folded upwardly and then downwardly against the walls 28 and corner extensions before the walls 27, and the corner extensions are swung upwardly and downwardly to oppose the base 26 and walls 28, thus causing the flaps 33 and 38 to be interposed between the corner extensions and walls 28. If desired, the opposing surfaces of the flaps 33 and 38 may be glued together or otherwise secured instead of employing a staple 44 or the like.

It will be noted from the foregoing that in all of the constructions illustrated, the parts of the box which overlie the folded corner-extensions and hold them in folded condition, whether it be the automatically operating laps of Figs. 1 to 14, inclusive, and Figs. 24, 25, and 26, or the tongues for insertion into slots in the constructions of Figs. 15 to 23, inclusive, are cut from the material of those sections of the corner-ex-

tensions which directly oppose certain of the box-walls, to points below the upper edges of these last referred to sections, these sections being sections 37 of Figs. 1 to 14 and 23, 24, and 25, and sections 70 of Figs. 15 to 23, inclusive. This is an important feature in boxes of the general character disclosed as the flaps usually provided on opposed walls of the box for holding the box in erected condition may be either wholly dispensed with, or the height of the same materially reduced, thereby effecting a great saving in the amount of material necessary to be employed in the manufacture of a stable construction of box.

While I have illustrated and described certain embodiments of my invention, I do not wish to be understood as intending to limit it thereto as the invention may be otherwise embodied, it being my intention to claim my invention as fully and completely as the prior state of the art will permit.

What I regard as new and desire to secure by Letters Patent is—

1. A box formed of a base, walls extending upwardly therefrom, corner-extensions connected with walls of the box and each formed of sections connected together along a diagonally-disposed line and lying in flatwise opposed relation and extending flatwise relative to adjacent box-walls, and members cut from the material of those sections of the corner-extensions which directly oppose said box-walls to points below the upper edges of said last-referred-to sections for overlappingly engaging the other sections of said extensions.

2. A box formed of a base, walls extending upwardly therefrom, corner-extensions connected with walls of the box and each formed of sections connected together along a diagonally-disposed line and lying in flatwise opposed relation and extending flatwise relative to adjacent box-walls, and laps cut from the material of those sections of the corner-extensions which directly oppose said box-walls to points below the upper edges of said last-referred-to sections, said laps being adapted to be sprung over the folded corner-sections in the erecting of the box and overlappingly engage therewith.

SIEGMUND BACHMANN.
